UNITED STATES PATENT OFFICE.

CHARLES E. MCKEAG, OF LOS ANGELES, CALIFORNIA.

BEDSTEAD ATTACHMENT.

SPECIFICATION forming part of Letters Patent No. 577,145, dated February 16, 1897.

Application filed June 30, 1896. Serial No. 597,590. (No model.)

To all whom it may concern:

Be it known that I, CHARLES E. MCKEAG, a citizen of the United States, residing at Los Angeles, in the county of Los Angeles and State of California, have invented certain new and useful Improvements in Bedstead Attachments, of which the following is a full, clear, and exact description, reference being had to the accompanying drawings, which form a part of this specification.

My invention relates to an improved bedstead attachment for the use of invalids or others in reading, eating, amusement, &c.; and my invention consists in certain features of novelty hereinafter described and claimed.

Figure I is a perspective view of my improved attachment, showing the same secured to one of the side rails of a bedstead. Fig. II is a perspective view of the clamp for securing the support to the side rail. Fig. III is a detail view showing the upper end of the vertical standard, the horizontal arm, and means for connecting the arm with the support. Fig. IV is a detail view taken on line IV IV, Fig. V, showing means for adjusting the telescopic section of the support. Fig. V represents a transverse section taken on line V V, Fig. IV. Fig. VI is a detail side elevation of the tray-adjusting device. Fig. VII is a detail view showing the connection between the tray-support and the inner end of the horizontal arm. Fig. VIII is a perspective view of the plate and the pin for connecting the fixed tray with the horizontal arm. Fig. IX is a perspective view of the fixed tray. Fig. X is a side elevation of the end piece, which is removably secured to the fixed tray. Fig. XI represents a side elevation of one of the removable side pieces for the fixed tray.

Referring to the drawings, 1 represents the vertical standard, composed of sections 2 3, the section 3 being adapted to telescope within the section 2, said sections being preferably made of gas or water pipe construction.

4 represents a collar having a portion of its inner surface of different diameter and provided with a shoulder 5, said collar fitting over the upper end of the section 2 of the standard, with the shoulder 5 resting on the upper end of said section 2.

6 represents a set-screw in the collar 4, said

set-screw serving to hold the section 3 of the standard in desired position as regards the section 2, into which it telescopes. The bottom of the standard is preferably held from sidewise movement by means of a point 7, adapted to enter a short distance into the floor. The standard is secured to the side rail 8 by means of a clamp 9, having a sleeve 10, which surrounds section 2 of the standard and which is adapted to slide thereon, it being secured at any point desired on the standard by means of a set-screw 11.

12 represents a lip on the clamp adapted 65 to engage the inner side of the rail 8, said lip preferably having teeth 13 on its lower inner edge in order to securely grasp the object to which the clamp is placed.

14 represents set-screws engaging the outer 70 face of the clamp, said set-screws having their inner ends preferably bearing against a block 15, said block pressing against the outer face of the rail 8.

16 represents a T-coupling secured to the 75 upper end of the section 3 of the standard.

17 represents a horizontal arm adapted to slide through the T-coupling 16 and having a series of apertures 18. The T-coupling 16 is provided with a central orifice 19, through 80 which the pin 20 may be inserted, said pin passing through one of the orifices 18 in the arm and extending into an orifice 21 in a plug 22, located in the upper end of the section 3 of the standard. By the means described the 85 arm 17 may be adjusted in its support in the standard.

23 represents a T-coupling secured to the inner end of the arm 17.

24 represents an adjustable shelf providing a support having a foot-piece 25, said shelf being adapted for the purpose of supporting a book or other reading matter and other similar articles.

26 represents a semicircular plate having a 95 lip 26^a, secured to the under side of the shelf 24, said plate having a series of orifices 27.

28 represents a post which is forked at 29, extending on each side of the plate 26 and pivoted thereto at 30, so as to swing freely 100 on said plate.

31 represents a set-screw by which the post 28 may be set at any angle desired in relation to the shelf 24, in order to give the shelf

the desired inclination. The post 28, fitting into the T-coupling 23 and being revoluble thereon, permits the shelf to be turned in either direction desired.

5 32 represents a set-screw by which the post may be set, and with it the shelf, in any desired position.

The shelf 24 may be removed at will and a support in the form of a tray 33 substituted 10 in its place, said tray 33 serving as a table, checker-board, or for other purposes.

15 34 represents a plate secured to the under side of the tray 33 and having a post 35, adapted to fit into the T-coupling 23. The tray 33 is provided with side pieces 36 and an end piece 37 for the purpose of preventing articles falling off of the tray. When desired, the sides and end piece may be removed, as they are held in connection with the tray 20 by means of pins 38 on their under sides.

My device is intended more especially for the sick-bed, but it is obvious that its use is not necessarily confined to such purposes.

25 My device can be adjusted to any point along the side rail of the bed, or can, if desired, be secured to the foot of the bed, and as the section 3 is movable in the section 2 it can be adjusted both as to vertical and horizontal movement. The arm 17 may be 30 swung either backward or forward, and perform a complete circle if desired; or the arm may be raised or lowered by adjusting set-screw 6 in order to give the proper height to

the tray or shelf. The shelf may be adjusted at any angle desired, and it may be turned 35 in a horizontal direction. Thus I provide a device that may be adjusted to any possible position desired.

I claim as my invention—

1. A bedstead attachment comprising a 40 standard, a clamp secured to the standard, a perforated plug located in the upper end of the standard, the T-coupling having a vertical perforation, the horizontal arm having a series of apertures and adjustable in the T- 45 coupling, a pin for securing the horizontal arm extending through the latter, through the T-coupling, and into the plug, a post secured to the horizontal arm, and a support secured to the post; substantially as described. 50

2. A bedstead attachment comprising a standard, a clamp secured to the standard, a horizontal arm secured to the standard, a T-coupling secured to the inner end of the arm, a post having a fork and secured to the T-coupling, a support, a semicircular plate formed with a lip and with a series of perforations, and secured to the support by the lip and a set-screw working through the fork and through a perforation in the plate; substantially as 55 described.

CHARLES E. MCKEAG.
